UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed June 24, 1922. Serial No. 570,565.

This invention relates to front-strike type-bar typewriting machines having a plurality of case-shifts, especially those having four-type type-bars.

5 An object of the invention is to produce a machine which is simple in construction, effective in operation and inexpensive to manufacture. Another object of the invention is to produce a machine capable of 10 a large variety of uses, and having other advantages. One of the objects is to provide for quickly removing as a unit the entire type-action, including the types and type-keys, together with the shift-keys, and 15 replacing the removed unit with another unit, the type-action of which may include a different set of types, and which also may be otherwise modified, if desired.

According to the present invention, the 20 platen is non-shiftable and the type-bar segment is shiftable from a normal position to three different case-shift positions. The shifting of the type-bar segment is accomplished by means of three independently-operable shift-keys. The segment is 25 capable of occupying two extreme positions and two intermediate positions, movable stops controlled by the shift-keys being provided for determining the intermediate 30 positions. More particularly, one of the keys shifts the segment from a normal intermediate position through a single space to an extreme position, another key shifts the segment from its normal position in 35 the opposite direction through one space to another intermediate position; and the third key shifts the segment from normal position through a double space to an extreme or final position. Key-controlled 40 movable stops determine the normal position and the other intermediate position of the segment.

According to another feature of the invention, the entire type-action, including 45 the type-bars and key-levers, also the shiftable segment, shift-levers, and stop mechanism for the segment, are all mounted upon a removable subsidiary frame, which is detachably mounted in the main framework 50 of the machine. This arrangement is such that the subsidiary frame and all the parts carried thereby may be readily assembled as a unit and attached to or detached from the main framework. Another subsidiary 55 frame carrying other corresponding or dif-

ferent parts and mechanisms may be substituted for the one removed.

Other features and advantages will hereinafter appear.

In the accompanying drawings, 60 Figure 1 is a substantially central front-to-rear vertical section of a typewriting machine embodying the present invention, with the various parts in their normal positions, for typing with the second type from 65 the top in the series of four types on each type-bar.

Figure 2 is a transverse vertical section, 70 with parts omitted, the section being taken at the front of the platen and type-bar segment and at the rear of the types and keyboard, and substantially at the offset line 2-2 of Figure 1.

Figure 3 is a partial plan view forwardly 75 of the platen, and shows the mounting of the vibrating ribbon-guide.

Figure 4 is a sectional view, on a reduced scale, similar to Figure 1, showing the first shift-key and means operated thereby for shifting the type-bar segment downwardly, 80 but showing the segment at its normal position, similarly to Figure 1.

Figure 5 is a similar view, but shows the segment shifted down by means of the first shift-key, to bring into use the first or 85 uppermost type in the series, the second and third shift-keys being shown at normal positions.

Figure 6 is a similar view, showing the segment shifted up to its intermediate case-shift position by means of the second shift-key, to bring into use the third type from 90 the top in the series.

Figure 7 is a similar view, showing the segment shifted up from normal position 95 through two case-shift spaces by means of the third shift-key, thereby to bring into use the lowermost or final type in the series.

The typewriting machine of the present invention is an improvement upon the 100 standard Underwood typewriting machine, and retains many advantageous features thereof. In the typewriting machine shown in the drawings as one embodiment of the invention, the platen 1 is non-shiftable and is journaled by means of its axle 2 directly upon a platen-carriage 3 which is mounted for letter-feed or reverse movement upon a main frame 4 of the machine. At its rear the carriage 3 is mounted to 105 110

travel on a rear rail 5 on the main frame 4. The main frame 4 comprises a front cross-bar 6, provided along its rear side with a shelf 7, forming a front rail on which runs a carriage-roller 8, journaled in a housing 9, carried by a front bar 10 of the platen-carriage 3. The front cross-bar 6 and the front carriage-bar 10 are sufficiently elevated to clear the extended four-type 10 type-bars, but are below the line of vision, so as to render the printing line on the platen visible by the typist. Certain features in the construction and arrangement of the front frame-bar 6 and front carriage-bar 10 and associated parts may be the same as are disclosed in my earlier co-pending application, Serial No. 568,691, filed June 16, 1922.

The carriage 3 may be drawn along in its 20 letter-feeding direction of movement by means of a usual spring-barrel (not shown), under the control of substantially the usual Underwood escapement mechanism, which is inounted upon an upstanding bracket 11, secured upon the main frame 4, so as to form virtually a part thereof. The escapement mechanism comprises a dog-rocker 12, pivoted at 13 upon the bracket 11, and having a downwardly-extending arm 14 by 25 which the dog-rocker 12 is operated, by means hereinafter described. The dog-rocker 12 carries fixed and loose dogs 15 and 16, to engage a ratchet-wheel 17, mounted on the upper end of the bracket 11 and 30 connected to a pinion 18, which engages with a suitable rack (not shown), carried by the platen-carriage 3.

The ribbon-vibrator, which is also mounted upon the main frame 4, includes a bell-crank-lever 19, pivoted at 20 upon a forwardly-extending arm of the bracket 11. The ribbon-vibrating bell-crank-lever 19 has a downwardly-extending arm 21 by which it is operated, by means hereinafter described. It also has a forwardly-extending arm 22, pivoted at 23 to the lower end of a vertically-vibrating ribbon-guide 24, which at its upper end is provided with eye-forming wing-portions 25 to guide a usual ribbon (not shown), and to cause the ribbon to cover and uncover the printing point on the platen as the ribbon-guide vibrates. The ribbon-guide 24 is guided on the main frame 4 of the machine by means of rearwardly and inwardly turned hook-portions 26 formed thereon, to engage in grooves formed in the sides of a guide-block 27, secured upon a transverse bar 28, which at its ends is secured to the side walls of the main frame 4, as shown in Figures 1 and 3. Since the ribbon-vibrator, comprising the bell-crank-lever 19 and the vibrating ribbon-guide 24, is mounted upon the main frame 4, and since the platen 1 is non-shiftable, the

necessity of providing means for shifting 65 the ribbon-vibrator is avoided.

According to the present invention, a removable subsidiary frame 29 is provided and is detachably mounted in the main frame 4 by means of screws 30, two at each side of 70 the machine, which pass through the side walls of the main frame 4, near the bottom thereof, and enter the lower part of the subsidiary frame 29. By removing the screws 30, the subsidiary frame 29, together with 75 all the parts and mechanisms carried thereby, to be hereinafter described, may be withdrawn from the main frame 4 at the bottom thereof. That may then be replaced by another subsidiary frame which may carry 80 either similar or modified mechanisms, and which also may carry a different set of types, for typing in another language, for example.

According to the present invention, a segment-frame is mounted in the subsidiary frame 29 for up-and-down case-shift movements from normal position to three different case-shift positions. In the machine shown in the drawings, the segment-frame 85 90 comprises a type-bar segment 31, secured by means of screws 32 to an upper cross-bar 33, provided at its ends with depending legs 34, which are connected together near their lower ends by means of a lower transverse 95 bar or bridge 35. A usual type-guide 36 is carried by the segment 31 at the front of the vibrating ribbon-guide 24, but, in carrying out the present invention, neither the type-guide 36 nor any part of the segment-frame 31 has any mechanical connection 100 105 with the vibrating ribbon-guide 24.

The means for guiding the segment-frame, including the type-bar segment 31, will be next described. A transverse rock-shaft 37 110 is journaled in the upper and rear part of the subsidiary frame 29 and at its ends has fixed thereon forwardly-extending arms 38 which normally are inclined slightly downwardly. At their forward ends these arms 38 are pivoted upon studs 39 which project from the outer sides of the segment-frame-legs 34 near the middle thereof, the rock-shaft 37 compelling the arms 38 to swing together as a unit and forming therewith a 115 rocking frame. A rock-arm 40 has a fulcrum-pivot at 41 upon the rear and lower part of the subsidiary frame 29, and is of the same length as, and extends forwardly in parallel relation to, the rock-arms 38. The rock-arm 40 at its forward end is pivoted at 42 to a lug 43 which projects down from the middle of the lower cross-bar or bridge 35 of the segment-frame. The segment-frame in its case-shift movements may 120 swing freely up and down upon the rock-arms 38 and 40, no other guiding means being required.

The type-bar segment 31 is provided with radial guide-slots 44, in which are pivoted, upon an arcuate fulcrum-wire 45, type-bars 46, to partake of the case-shift movements of the segment 31, the number of type-bars 46 in the set being about equal to those commonly employed in the standard Underwood or other single-shift typewriting machine. Each type-bar 46 carries an extending type-block 47, having four types, 48, 49, 50 and 51, arranged in a series thereon and numbered from the uppermost downwardly, for convenience of description. In the typewriting machine shown in the drawings, normally, or without case-shifting, the second type 49 in the series will strike at the printing point upon the front of the platen 1, as indicated in Figure 1 by the arcuate broken line 52, and as shown in Figure 4 by the upraised type-head 47, the shiftable segment 31 then having a corresponding normal intermediate position.

In order to print by means of the first or uppermost type 48 in the series, the type-bar segment 31 is shifted downwardly to its lowermost or final case-shift position, shown in Figure 5; to print by means of the third type 50 in the series, the segment 31 is shifted upwardly from its normal position to an intermediate case-shift position, shown in Figure 6; while to print by means of the last or lowermost type 51 in the series, the segment 31 is shifted upwardly from its normal intermediate position through two case-shift spaces or distances to its uppermost or final case-shift position, shown in Figure 7. According to one way of carrying out the invention, it may be desirable to have the second type 49 print the small letters of the alphabet, to have the first type 48 print the capital letters, and to have the remaining two or lower types 50 and 51 print miscellaneous characters, such as figures and various commonly-used arbitrary symbols and signs. It is understood, however, that the invention is not limited to the above-noted particular arrangement of the types, nor is it limited to the particular case-shifting arrangement above mentioned. On the other hand, other arrangements may be effected according to any particular requirements or demands, depending upon the language to be written, or upon other requirements, as the case may be. A type-rest 53 is provided for the type-blocks 47, and is supported upon the segment-frame to shift therewith by means of forwardly-extending bars or arms 54, of which one is shown in Figure 1.

The segment-frame, including the type-bar segment 31, is automatically returnable from any of its case-shift positions to its normal intermediate position. It is automatically returned by gravity from its uppermost and from its intermediate case-

shift positions to its normal position. It is automatically returned to its normal intermediate position from its lower case-shift position by spring means. This comprises a spring 55, at each side of the machine, 70 acting between the subsidiary frame 29 and a lifting arm or lever 56, fulcrumed at 57 upon the subsidiary frame, the forward ends of the levers 56 engaging beneath raised end-portions 58 of the bridge-bar 35, to the main or middle portion of which the end-portions 58 are connected by means of short upright portions 59, as shown in Figure 2. Each segment-lifting lever at 56 is provided with a tail 60 to abut against a stop-pin 61 80 on the subsidiary frame 29, so as to render the spring 55 ineffective when the segment-frame has reached its normal position.

The means for case-shifting the segment-frame from its normal intermediate position to any of its three case-shift positions includes a transverse rock-shaft 62, journaled in the lower part of the subsidiary frame 29 forwardly of the segment-frame, and having fixed upon its ends rearwardly-extending rock-arms 63. The arms 63 are provided with slotted or forked ends to engage studs 64 carried by lugs 65 which extend downwardly from the lower ends of the segment-frame-legs 34, so that by rocking the rock-shaft 62 in one direction or reversely, the segment-frame will be correspondingly lowered or raised.

In order to shift the segment-frame downwardly from its normal intermediate position at which printing is done by means of the second or small-letter types 49, to a final case-shift position to print by means of the uppermost or capital-letter types 48, as shown in Figure 5 by the upraised type-head 47, a first shift-key 66 is provided. This is carried by a first shift-lever 67, located at the right side of the machine and pivoted upon a fulcrum-rod 68 carried by a slotted transverse bar 69 which forms an upper rear tie-bar for the subsidiary frame 29 at the rear of the lower part of the segment 31. When the shift-key 66 is depressed, a downwardly-projecting lug 70 on the shift-lever 67, after traversing an intervening space provided for purposes which will hereinafter appear, is brought into engagement with a laterally-projecting lug 71 upon the forward end of a short intermediate lever 72 of the first order. The lever 72 is fulcrumed upon a stud 73 projecting inwardly from the adjacent side wall of the subsidiary frame 29. The continued downward movement of the shift-key 66 raises a pin 74 carried by the forward end of the intermediate lever 72. The pin 74 engages in a slot formed in the forward end of a short forwardly-extending rock-arm or lever 75 fixed upon the rock-shaft 62, to rock the rock-shaft 62 in a clockwise 125 direction.

direction, as viewed in Figures 4 and 5, thereby depressing the rock-arms 63 carried by the rock-shaft 62 and imparting a downward case-shift movement to the type-bar segment 31. When the shift-key 66 is released, the segment-frame will be automatically restored to its normal position by the springs 55, and the shift-lever 67 will be raised by its spring 76. It will be noted that the inter-connected rocking levers 72 and 75 form elements of a compound lever, and these elements are of such relative lengths as to impart the correct downward throw to the segment-frame to shift the latter through a single case-shift space when the shift-key 66 is depressed.

Inasmuch as it is occasionally desired to write one or more words, or one or more lines, in capital letters, a latch or locking device is provided for holding down the first shift-lever 67. A latch-lever 77, having at its lower end a hook 78 and at its upper end a finger-piece 79, is pivoted at 80 upon the shift-lever 67. A slotted comb 81, having an upper bar 82, which forms a stop for the shift-lever 67, as well as for the other shift-levers and key-levers, is carried at the front of the subsidiary frame 29. At its lower margin this comb 81 carries a forwardly-projecting member 83, which forms a catch or keeper for the hook 78, with which, as is clearly shown in Figure 5, the hook normally does not engage, the shift-key 66 thereby being normally left free to rise after each actuation. When it is desired to lock the shift-lever 67 down, the finger-piece 79 of the latch-lever 77 is drawn rearwardly, to engage the hook 78 with the latch or keeper 83; and, obviously, by a reverse operation, the hook 78 may be disengaged when desired. The disengaging movement of the latch 77 may be limited by a small stud 84 on the shift-lever 67, and preferably a light spring 85 is provided for maintaining the latch 77 in its disengaged position.

For shifting the type-bar segment 31 upwardly from its normal position to its intermediate case-shift position, to print by means of the third type 50 in the series, a second shift-key 86, Figures 1 and 6, is provided upon a second shift-lever 87, located at the left side of the machine, Figure 2, and pivoted upon the fulcrum-rod 68. When the second shift-key 86 is depressed, during the initial part of its movement, lost motion, the purposes of which will hereinafter appear, will be taken up between a downwardly-projecting lug 88 on the shift-lever 87 and a laterally-projecting lug 89 upon the forward end of a lever-arm 90 fixed upon the segment-shifting rock-shaft 62. Further depression of the shift-key 86 will rock the rock-shaft 62 in a counter-clockwise direction, as viewed in Figures 1

and 6. It will thereby lift the segment-frame by means of the rock-arms 63 from its normal position, shown in Figures 1 and 4, through a single case-shift space or distance to its intermediate case-shift position, shown in Figure 6, for printing by means of the third type 50, by the upraised type-head 47. The lever-arm 90 is made of the proper length to impart the correct case-shift movement to the segment-frame when the shift-key 86 is operated. When the shift-key 86 is released, the shift-lever 87 will be raised by its spring 91 to its normal position, at which it will be stopped by the comb-bar 82.

For shifting the type-bar segment 31 upwardly from its normal position, shown in Figure 1, through two case shift spaces or distances to its upper final case-shift position, to print by means of the lowermost types 51, as shown by the upraised type-head 47 in Figure 7, a third shift-key 92 is provided upon a third shift-lever 93, pivoted upon the fulcrum-rod 68. After taking up the intervening lost motion provided for purposes which will hereinafter appear, a downwardly-projecting lug 94 on the third shift-lever 93 comes into engagement with a laterally-projecting lug 95 provided upon the forward end of a lever-arm 96 fixed on the segment-shifting rock-shaft 62. Further downward movement of the shift-key 92 will then rock the rock-shaft 62 in a counter-clockwise direction, as viewed in Figures 1 and 7, and will accordingly shift the segment-frame upwardly by means of the rock-arms 63 on the rock-shaft 62. The lever-arm 96 is made of the proper length, so that case-shift movement will be imparted to the segment 31 through two case-shift spaces, this lever-arm 96 for the third shift-lever 93 being considerably shorter than the corresponding lever-arm 90 for the second shift-lever 87, as will be evident by an inspection of Figure 1 and by a comparison of Figures 6 and 7. When the third shift-key 92 is released, a spring 97 will raise the shift-lever 93 to its normal position against the comb-bar 82.

By reason of the relative locations and arrangement of, and spacing or lost motion provided between, the shift-lever lugs 70, 88 and 94 and the respective lever-arm lugs 71, 89 and 95 operated thereby, when the first shift-key 66 is depressed the lever-arm lugs 89 and 95 will rise clear of and to the rear of the lugs 88 and 94 carried by the second and third shift-levers, as is shown in dotted lines in Figure 5. Similarly, when the second shift-key 86 or the third shift-key 92 is depressed, the lever-arm lug 71 will rise at the rear of and clear of the first shift-lever lug 70, as will be seen from Figure 4.

Preferably means are provided to relieve the second and third shift-keys 86 and 92

of a portion of the weight of the segment-frame, and for this purpose a counterbalance spring 98 is arranged to act upon the segment-frame-shifting rock-shaft 62, the spring 98 having a tendency to rotate the rock-shaft 62 in a counterclockwise direction, as viewed in Figures 1, 6 and 7.

A shift-key-controlled stop mechanism for the shiftable segment-frame is mounted on the detachable subsidiary frame 29, to be removed therewith from the main frame 4. A transverse rock-shaft 99 at the rear of the segment-frame and adjacent to the lower tie-bar or bridge 35 thereof is journaled in the side walls of the subsidiary frame 29. The rock-shaft has fixed upon each of its outwardly-projecting ends an upstanding stop-carrying arm or plate 100 which extends up in spaces provided between the end walls of the main frame 4 and the end walls of the subsidiary frame 29 nearly to the top of the segment-frame in its normal or unshifted position. In the illustrated embodiment of the invention, the segment-frame-stops are integrally formed upon the upper end portions of the plates 100 and thereby move as a unit therewith.

Upper and lower stop-shoulders 101 and 102 have spaced overlapping portions which normally engage above and below an outwardly-projecting pin or stud 103 carried by an ear or lug 104 which projects rearwardly from the adjacent segment-frame-leg 34. The shiftable segment-frame, including the type-bar segment 31, is thereby normally locked at its normal position against movement either upwardly or downwardly, but, by moving the stop-carrying members or plates 100 rearwardly from their normal position, the segment-frame may be shifted downwardly, and, by moving these plates forwardly from their normal position, the segment-frame may be shifted upwardly. When the segment-frame returns from its lower case-shift position it will be positively stopped at its normal position by the pin 103 abutting against the non-overlapping or forward portions of the upper stop-shoulders 101. Similarly when the shiftable segment frame returns from either of its upper case-shift positions it will be positively stopped at its normal position by the pins 103 abutting against the rear or non-overlapping portions of the lower stop-shoulders 102. The overlapped shoulders 101 and 102 form a combined stopping device and normally effective locking device for the segment-frame.

For positively stopping the segment-frame when it is shifted upwardly by the second shift-key 86, the stop-pin 103 will abut against an intermediate stop-shoulder 105, located upon the plate 100 at the rear of and at a proper distance above the upper locking-shoulder 101, when the stop-carry-

ing plate 100 is moved forward sufficiently to free the pin 103 from the upper locking shoulder 101. The lower case-shift position of the segment-frame, which is a final case-shift position, is positively determined when the the segment-frame is shifted downwardly by means of the first shift-key 66, by the pin 103 abutting against a lowermost stop-shoulder 106 formed upon the plate 100. The stop-shoulder 106 is at the front 70 of the plate 100 below the lower locking shoulder 102, the plate 100 being moved rearwardly to free the pin 103 from the lower locking shoulder 102. The shiftable segment-frame is positively stopped at its upper case-shift position, to which it is shiftable by means of the third shift-key 92, by the stop-pin 103 abutting against an uppermost stop-shoulder 107. This stop-shoulder is provided at a proper distance 85 above and at the rear of the intermediate case-shift stop-shoulder 105, the stop-carrying plates 100 being rocked forward a sufficient distance so that both the upper locking shoulder 101 and the intermediate case-shift stop-shoulder 105 will clear the pin 103 as the segment-frame moves to its upper final case-shift position. 90

For causing the stop-carrying plates 100 to be rocked either backwardly or forwardly, to render the different above-described stop-shoulders effective, as may be desired, a shift-key-controlled transverse rock-shaft 108 is provided. This rock-shaft is locked at the front of the segment-frame and just above the shift-levers, is journaled in the end walls of the subsidiary frame 29, and has fixed upon its outwardly-projecting ends downwardly and slightly rearwardly extending lever-arms 109, each of which is connected to the corresponding stop-carrying plate 100 by means of an upwardly-inclined link 110. 100

The stop-carrying plates 100 are normally urged rearwardly by means of springs 111. During the initial part of the downward movement of the first shift-lever 67 and before its lug 70 comes into contact with the intermediate lever-lug 71 for shifting the segment-frame downwardly, as hereinbefore described, a cam 112 on the shift-lever 67 is actuated. This cam will permit a limited amount of forward and downward movement of a pin or cam-follower 113 carried by an upwardly and forwardly projecting lever-arm 114 fixed upon the stop-controlling rock-shaft 108. Springs 111 will be permitted to move the stop-carrying plates 100 rearwardly from their normal positions, shown in Figures 1 and 4, 115 until their lower locking shoulders 102 disengage the pins 103 carried by the segment-frame. The further downward movement of the shift-lever 67 will then shift the segment-frame downwardly, as hereinbefore 120

125

130

described, until it is positively stopped by the pins 103 abutting against the lowermost stop-shoulders 106 at the final lower case-shift position of the segment-frame, as shown in Figure 5. When the first shift-key 66 is released and the shift-lever 67 rises, the segment-frame will be lifted by the springs 55 until it is positively stopped by the pins 103 abutting against the forward or non-overlapping portions of the upper locking shoulders 101 at the normal position of the segment-frame. The further rising of the shift-lever 67 will force the follower-pin 113 rearwardly, thereby, through the connections hereinbefore described, moving the stop-carrying plates 100 forwardly to their normal positions so that pins 103 on the segment-frame are between the overlapping portions of the opposed stop-shoulders 101 and 102, as shown in Figures 1 and 4, thereby to lock the segment-frame at its normal position.

During the initial part of the downward movement of the second shift-lever 87, a cam 115 thereon acts upon a pin or cam-follower 116, carried by a second lever-arm 117 fixed upon the stop-controlling rock-shaft 108 to rotate the latter in a clockwise direction, as viewed in Figures 1 and 6. Thereby, through the connections hereinbefore described, the stop-carrying plates 100 are moved, against the tension of their springs 111, forwardly from their normal positions, shown in Figure 1. This distance of movement is such that the upper locking shoulders 101 are moved clear of the pins 103 on the segment-frame, whereupon the further downward movement of the shift-lever 86 will shift the segment-frame upwardly, as hereinbefore described, from its normal position, until it is positively stopped by the pins 103 abutting against the intermediate stop-shoulders 105 at the intermediate case-shift position of the segment-frame, as shown in Figure 6. When the second shift-key 86 is released and the shift-lever 87 rises, first the segment-frame will be restored by gravity to its normal position, where it will be positively stopped by the pins 103 abutting against the non-overlapping portions of the lower locking shoulders 102. The release of the cam-follower 116 by the shift-lever cam 115 will enable the spring 111 to move the stop-carrying plates 100 rearwardly. This will restore them to their normal positions, where they will be stopped by reason of the cam-follower-pin 113 coming into engagement with the cam 112 carried by the first shift-lever 67.

During the initial part of the downward movement of the third shift-lever 93, a cam 118 provided thereon acts upon a cam-follower 119 carried by the lever-arm 117 fixed upon the stop-controlling rock-shaft 108 to rock this shaft in a clockwise direction, as

viewed in Figures 1 and 7, to a greater extent than it was rocked by the second shift-lever cam 115. Thereby, through the connections hereinbefore described, the stop-carrying plates 100 are moved forwardly, 70 against the tension of their springs 111, to an extent which will not only free the pins 103 from the upper locking shoulders 101, but which also will clear these pins of the intermediate stop-shoulders 105. Further 75 downward movement of the third shift-lever 87 will shift the segment-frame upwardly, as hereinbefore described, from its normal position, shown in Figure 1, through two case-shift spaces or distances, until it is positively stopped at its uppermost case-shift position by the pins 103 abutting against the uppermost stop-shoulders 107, as shown in Figure 7. Upon the release of the third shift-key 92 and the rising of the shift-lever 93, the segment-frame will be automatically restored by gravity to its normal position, where it will be positively stopped by the pins 103 abutting against the rear portions of the lower locking shoulders 102. The continued upward movement of the shift-lever 93 will then cause the cam 118 to release the follower-pin 119, thereby enabling the springs 111 to move the stop-carrying plates 100 rearwardly until they are restored to their normal positions with the follower-pins 113 abutting against the cam 112 on the first shift-lever 67.

The type-action shown as embodied in the machine of the present invention has features in common with the corresponding structure disclosed in the aforesaid earlier application, and, in the present invention, is mounted upon the detachable subsidiary frame 29 to be removed therewith from the main frame 4 and from the parts of the machine or mechanisms carried thereby. Upstanding sub-levers 121 of the first order are pivoted in guide-slots 122 in the segment-frame-bridge 35, upon a fulcrum-rod 123 carried by the segment-frame-bridge 35, which, by reason of the different lengths of the sub-levers, is bowed or curved downwardly throughout its middle portion, the elevated end-portions 58 thereof providing space for the shift-levers 67, 87 and 93. The upper ends of the sub-levers 121 carry pins 124 which work in curved slots 125 provided in the type-bars 46. Downwardly-extending portions 126 of key-levers 127, carrying type-keys 128, are pivoted with the shift-levers upon the fulcrum-rod 68 carried by the upper rear cross-bar or tie-bar 69 of the subsidiary frame 29. The lower ends of the sub-levers 121 are pivotally connected to the downwardly-extending portions 126 of the key-levers by means of substantially horizontal links 129. These latter provide for the hereinbefore-described case-shift movements of the segment-frame, including the type-bar 130

segment 31 and sub-lever-carrying bridge 35. The key-levers 127 are raised to normal position against the comb-bar 82 by means of springs 130.

5 It is to be noted in this connection that the entire type-action, including the key-levers 127, operating links 129, sub-levers 121 and type-bars 46, as well as the segment-frame and the hereinbefore-described guiding 10 means therefor, are mounted upon, so as to be removable with, the detachable subsidiary frame 29.

The apparatus for operating the escapement mechanism has features in common 15 with the corresponding structure disclosed in the aforesaid prior application, and is mounted on the main frame 4. An escapement-operating rock-shaft 131, journaled in the end walls of the main frame 4, carries 20 near its middle, a short upstanding lever-arm 132, which engages at the rear the downwardly-extending dog-rocker-arm 14. Adjacent its ends the rock-shaft 131 has fixed thereon a pair of downwardly and forwardly extending bail-arms 133, which, at 25 their lower ends, carry a universal bar 134 operable by means of lugs 135 provided upon the rear edges of the downwardly-extending key-lever-portions 126. The operating 30 lugs 135 are normally out of contact with the universal bar 134, as shown in Figure 1, so that the dog-rocker 12 will not be operated until near the end of a key-lever-stroke. A spring 136 returns the universal bar 134 35 to normal position with the upstanding arm 132 against a stop-lug 137 provided on the bracket 11.

The mechanism for operating the hereinbefore-described ribbon-vibrator is mounted 40 on the main frame 4 and has features in common with the corresponding structure disclosed in the aforesaid prior application. A rock-shaft 138, journaled at its ends in the side walls of the main frame 4, carries 45 near its middle a short upstanding lever-arm 139 provided with a pin 140 which engages in a radial slot formed in the lower end of the downwardly-extending arm 21 of the bell-crank-lever 19. Adjacent its ends 50 the rock-shaft 138 has fixed thereon a pair of downwardly-extending bail-arms 141 which, at their lower ends, carry a universal bar 142 to be operated by rearwardly-projecting lugs 143 provided upon the downwardly-extending portions 126 of the key-levers above the escapement-operating lugs 135. A restoring spring 144 is provided for 55 the ribbon-vibrating universal bar 142.

The escapement-mechanism-operating universal bar 134 and the ribbon-vibrating universal bar 142 may swing freely upon their respective bail-arms 133 and 141 between the side walls of the detachable subsidiary frame 29. This is arranged so that the latter may be readily withdrawn from the

main frame 4 downwardly away from the universal bars 134 and 142, leaving both these universal bars upon their respective shafts 131 and 138 on the main frame 4.

A substantially usual space-bar 145 is provided 70 and is carried at its ends upon the forward ends of spacing levers 146 which may be of substantially the same form as the key-levers 127 and may be pivoted therewith at 68 on the detachable subsidiary frame 29 to be removed.

A line-locking bail-rod 147, which is normally free from, but is engageable in the usual way, with hooks 148 on the key-levers 127, is carried at its ends upon the upstanding bail-arms 149 which at their lower ends are pivoted at 150 upon the side walls of the main frame 4 adjacent the bottom thereof. When the subsidiary frame 29 is detached from the main frame 4, it can be readily seen from Figures 1 and 2 that the subsidiary frame 29 and key-levers 127 may freely move downwardly away from the line-locking bail-rod 147 between the bail-arms 149 and their pivots 150.

Besides its upper tie-bar 69, the subsidiary frame 29 has a rear lower tie-bar 151 which, by means of a lug 152, carries the fulcrum-pivot 41 for the segment-frame-guiding rock-arm 40. The subsidiary frame also has a front lower frame-bar or tie-bar 153 to which the return springs 130 for the key-levers 127 are shown as connected.

When the subsidiary frame 29 is detached and removed from the rest of the machine, in the manner hereinbefore described, it will carry with it the entire type-action including the type-bars 46 and type-keys 128, and will also carry with it the three shift-keys 66, 86 and 92, together with the shift-key-controlled stop mechanism for the shifttable segment-frame, and the space-key 145. This will leave upon the main frame the platen 1, the platen-carriage 3, the carriage-feeding escapement mechanism and the operating mechanism therefor, including the universal bar 134, the ribbon-vibrator and the operating mechanism therefor, including the universal bar 142 and the line-locking bail-rod 147. When the subsidiary frame 29, together with the parts carried thereby, is thus detached and removed from the main frame 4, it may be replaced by another similar subsidiary frame, of which the type-bars may carry a different set of types, for example, for typing in a different language, and also, if desired, by reason of the peculiarities of the alphabet of any particular language or for other reasons, the order in which the case-shifting is effected from one type to another may be modified.

Variations may be resorted to within the scope of the invention, and portions of the improvements may be used without others.

Having thus described my invention, I claim:

1. In a front-strike typewriting machine, in combination, a platen, a type-bar segment, a set of type-bars pivoted on the segment and each having a plurality of types arranged in a series longitudinally thereof, said platen and segment being relatively shiftable members, and a case-shift mechanism including a first shift-key for shifting the shiftable member from a normal intermediate position in one direction through a single case-shift space or distance, a second shift-key for shifting said shiftable member from a normal intermediate position through a single case-shift space in the reverse direction to which the segment is shiftable by the other shift-key, stops for limiting the case-shift movements of said shiftable member, and a movable device selectively movable in opposite directions by different shift-keys arranged to stop the shiftable member at either up or down shift thereof and at the intermediate normal position of said shiftable member upon its return from either of its said case-shift printing positions.
2. In a front-strike typewriting machine, in combination, a non-shiftable platen, a set of shiftable type-bars each swingable to strike the platen and having four types thereon arranged in a row or series longitudinally thereof, and means for shifting said set of type-bars from a normal intermediate position in one direction through a single case-shift space or distance to a final case-shift position, or in the other direction through a single case-shift space or distance to an intermediate case-shift position, or through two case-shift spaces or distances to another final case-shift position.
3. In a front-strike typewriting machine, in combination, a non-shiftable platen, a set of shiftable type-bars each swingable to strike the platen and having four types thereon arranged in a row or series longitudinally thereof, and means for shifting said set of type-bars downwardly from a normal intermediate position for printing with the second type from the top in the series to a final case-shift position to print with the first or uppermost type in the series, or upwardly from its normal position to an intermediate case-shift position to print with the third type from the top in the series, or upwardly from its normal position to another final case-shift position to print with the last or lowermost type in the series.
4. In a front-strike typewriting machine, in combination, a non-shiftable platen, a traveling carriage therefor, an up-and-down shiftable type-bar segment capable of occupying two final positions and two intermediate positions, a set of type-bars pivoted on the segment to shift therewith and each having four types thereon arranged in a row or series longitudinally thereof, three independently-operable shift-keys for respectively shifting the segment from normal position to any selected one of three case-shift positions, stops for the segment for determining its final positions, and movable stops controlled by the shift-keys for stopping the segment at its intermediate positions.
5. In a front-strike typewriting machine, in combination, a non-shiftable platen, a traveling carriage therefor, an up-and-down shiftable type-bar segment, a set of type-bars pivoted on the segment to shift therewith and each having four types thereon arranged in a row or series longitudinally thereof, a first shift-key for shifting the segment from an intermediate normal position in one direction through a single case-shift space or distance to a final case-shift position, a second shift-key for shifting the segment from its normal position in the other direction through a single case-shift space or distance to an intermediate case-shift position, a third shift-key for shifting the segment from its normal position in the same direction that it is shiftable by said second shift-key through two case-shift spaces or distances to another final case-shift position, stops for the segment for determining its final case-shift positions, and movable stops controlled by the shift-keys to determine the normal position and the intermediate case-shift position of the segment.
6. In a front-strike typewriting machine, in combination, a non-shiftable platen, a traveling carriage therefor, an up-and-down shiftable type-bar segment, a set of type-bars pivoted on the segment to shift therewith and each having four types thereon arranged in a row or series longitudinally thereof, a first shift-key for shifting the segment downwardly from a normal intermediate position for printing with the second type from the top in the series to a final case-shift position to print with the first or uppermost type in the series, a second shift-key for shifting the segment upwardly from its normal position to an intermediate case-shift position to print with the third type from the top in the series, a third shift-key for shifting the segment upwardly from its normal position to another final case-shift position to print with the last or lowermost type in the series, stops for the segment for determining its final case-shift positions when shifted by said first or by said third shift-key, a shift-key-controlled movable stop to determine the intermediate case-shift position of the segment, and shift-key-controlled movable stops for stopping the segment at its normal position upon its return from any of its case-shift positions.
7. In a front-strike typewriting machine,

in combination, a non-shiftable platen, a traveling carriage therefor, an up-and-down shiftable type-bar segment, a set of type-bars pivoted on the segment to shift therewith and each having four types thereon arranged in a row or series longitudinally thereof, a first shift-key for shifting the segment from an intermediate normal position in one direction through a single case-shift 10 space or distance to a final case-shift position, a second shift-key for shifting the segment from its normal position in the other direction through a single case-shift space or distance to an intermediate case-shift position, a third shift-key for shifting the segment from its normal position in the other direction that it is shiftable by said second shift-key through two case-shift spaces or distances to another final case-shift position, 20 stops for the segment for determining its final case-shift positions, movable stops controlled by the shift-keys to determine the normal position and the intermediate case-shift position of the segment, said segment 25 when shifted upwardly being returnable by gravity to normal position, and means for automatically lifting said segment to normal position when shifted downwardly.

8. In a front-strike typewriting machine, 30 in combination, a non-shiftable platen, a traveling carriage therefor, an up-and-down shiftable type-bar segment, a set of type-bars pivoted on the segment to shift therewith and each having four types thereon arranged in a row or series longitudinally thereof, a first shift-key for shifting the segment from an intermediate normal position in one direction through a single case-shift 35 space or distance to a final case-shift position, a second shift-key for shifting the segment from its normal position in the other direction through a single case-shift space or distance to an intermediate case-shift position, a third shift-key for shifting the segment from its normal position in the same direction that it is shiftable by said second shift-key through two case-shift spaces or distances to another final case-shift 40 position, stops for the segment for determining its final case-shift positions, movable stops controlled by the shift-keys to determine the normal position and the intermediate case-shift position of the segment, said segment 45 when shifted upwardly being returnable by gravity to normal position, a spring for automatically lifting said segment to normal position when shifted downwardly, and means to render the segment-lifting spring ineffective to further lift the segment when the lifted segment reaches its 50 normal position.

9. In a front-strike typewriting machine, 55 in combination, in non-shiftable platen, a platen carriage therefor, an up-and-down shiftable type-bar segment, a set of type- 60

bars pivoted on the segment to shift therewith and each having four types thereon arranged in a row or series longitudinally thereof, a first shift-key for shifting the segment downwardly from a normal intermediate position for printing with the second type from the top in the series to a final case-shift position to print with the first or uppermost type in the series, a second shift-key for shifting the segment 70 upwardly from its normal position to an intermediate case-shift position to print with the third type from the top in the series, a third shift-key for shifting the segment upwardly from its normal position 75 to another final case-shift position to print with the last or lowermost type in the series, stops for the segment for determining its final case-shift positions when shifted by 80 said first or by said third shift-key, a shift-key-controlled movable stop to determine the intermediate case-shift position of the segment, shift-key-controlled movable stops for stopping the segment at its normal position upon its return from any of its case-shift positions, said segment being returnable by gravity from its upper case-shift 85 positions to its normal position, and means for automatically returning said segment 90 from its lower case-shift position to its normal position.

10. In a front-strike typewriting machine, 95 in combination, a non-shiftable platen, a platen carriage therefor, an up-and-down shiftable type-bar segment, a set of type-bars pivoted on the segment to shift therewith and each having four types thereon arranged in a row or series longitudinally thereof, a first shift-key for shifting the segment downwardly from a normal intermediate position for printing with the second type from the top in the series to a final case-shift position to print with the first or uppermost type in the series, a second shift-key for shifting the segment 100 upwardly from its normal position to an intermediate case-shift position to print with the third type from the top in the series, a third shift-key for shifting the segment upwardly from its normal position 105 to another final case-shift position to print with the last or lowermost type in the series, stops for the segment for determining its final case-shift positions when shifted by 110 said first or by said third shift-key, a shift-key-controlled movable stop to determine the intermediate case-shift position of the segment, shift-key-controlled movable stops for stopping the segment at its normal position upon its return from any of its case-shift positions, said segment being returnable by gravity from its upper case-shift 115 positions to its normal position, and means for automatically returning said segment 120 from its lower case-shift position to its normal position.

11. In a front-strike typewriting machine, 125 in combination, in non-shiftable platen, a platen carriage therefor, an up-and-down shiftable type-bar segment, a set of type-bars pivoted on the segment to shift therewith and each having four types thereon arranged in a row or series longitudinally thereof, a first shift-key for shifting the segment downwardly from a normal intermediate position for printing with the second type from the top in the series to a final case-shift position to print with the first or uppermost type in the series, a second shift-key for shifting the segment upwardly from its normal position to an intermediate case-shift position to print with the third type from the top in the series, a third shift-key for shifting the segment upwardly from its normal position to another final case-shift position to print with the last or lowermost type in the series, stops for the segment for determining its final case-shift positions when shifted by 130 said first or by said third shift-key, a shift-key-controlled movable stop to determine the intermediate case-shift position of the segment, shift-key-controlled movable stops for stopping the segment at its normal position upon its return from any of its case-shift positions, said segment being returnable by gravity from its upper case-shift positions to its normal position, means for automatically returning said segment 135 from its lower case-shift position to its normal position.

- lower case-shift position to its normal position, and stop means including an abutment for rendering the segment-lifting spring ineffective to further lift the segment when 5 the segment has reached its normal position.
11. In a front-strike typewriting machine, in combination with a platen, an up-and-down shiftable type-bar segment, a combined stop-device and normally effective locking-device for stopping and holding the segment at a normal intermediate position, a first shift-key which when depressed first renders said locking-device ineffective and then shifts the segment downwardly, a second shift-key which when depressed first renders said locking-device ineffective and then shifts the segment upwardly, and a third shift-key which when depressed first renders said locking-device ineffective and then shifts the segment upwardly through a greater distance than it is shiftable by said second shift-key.
12. In a front-strike typewriting machine, in combination with a platen, an up-and-down shiftable type-bar segment, a combined stop-device and normally effective locking-device for stopping and holding the segment at a normal intermediate position, a first shift-key which when depressed first renders said locking-device ineffective and then shifts the segment downwardly to a final case-shift position, a second shift-key which when depressed first renders said locking-device ineffective and then shifts the segment upwardly to an intermediate case-shift position, and a third shift-key which when depressed first renders said locking-device ineffective and then shifts the segment upwardly to a greater extent than it is shiftable by said second shift-key and to a final upper case-shift position, stops for determining the final case-shift positions of the segment, and a shift-key-controlled movable stop for determining the intermediate case-shift position of the segment.
13. In a front-strike typewriting machine, in combination with a platen, a type-bar segment shiftable up and down from a normal intermediate position to upper and lower case-shift positions and automatically returnable from its case-shift positions to its normal position, a combined stop-device and normally effective locking-device for stopping and holding the segment at its normal or intermediate position, said device comprising upper and lower spaced and partly overlapping abutment shoulders connected together to move as a unit, a pin or projection on the segment to strike against said upper abutment shoulder for stopping the segment upon its return to normal position from lower case-shift position and striking against said lower abutment shoulder for stopping the segment upon its return to normal position from upper case-shift position and to engage between the overlapping portions of said abutment shoulders to lock the segment at normal position, a first shift-key which when depressed first moves said device to enable the segment to be shifted downwardly and then by further movement shifts the segment downwardly, a second shift-key which when depressed first moves said device to enable the segment to be shifted upwardly and then by further movement shifts the segment upwardly, and stops for determining said upper and lower case-shift positions of the segment.
14. In a front-strike four-type type-bar typewriting machine, in combination, a non-shiftable platen, an up-and-down shiftable type-bar segment, a combined stop-device and locking-device for the segment, said device comprising three abutment-forming stop shoulders connected together to move as a unit, two of said shoulders being overlapped in spaced relation and the third shoulder being at a different level from said overlapped shoulders, a pin or projection carried by the segment to engage between said overlapped shoulders for locking the segment at a normal intermediate position of the segment, said upper overlapped shoulder being engageable by said pin to stop the segment upon its return to normal position from a lower case-shift position, and said lower overlapped shoulder being engageable by said pin to stop the segment upon its return from an upper case-shift position, and said third shoulder being engageable by said pin to stop the segment at an intermediate case-shift position, a first shift-key which when depressed first moves said device to cause one of said overlapped shoulders to clear said pin and then shifts the segment in one direction to a final case-shift position, a second shift-key, which when depressed first moves said device to cause said other overlapped shoulder to clear said pin and then shifts the segment to an intermediate case-shift position with said pin against said third shoulder, a third shift-key which when depressed moves said device to cause one of said overlapped shoulders and also said third shoulder to clear said pin and then shifts the segment to a final case-shift position beyond its said intermediate case-shift position, and stops for determining the final case-shift positions of the segment.
15. In a front-strike four-type type-bar typewriting machine, in combination, a non-shiftable platen, an up-and-down shiftable type-bar segment, a combined stop-device and locking-device for the segment, said device comprising three abutment-forming stop shoulders connected together to move as a unit, two of said shoulders being overlapped in spaced relation and the third

shoulder being at a different level from said overlapped shoulders, a pin or projection carried by the segment to engage between said overlapped shoulders for locking the 5 segment at a normal intermediate position of the segment, said upper overlapped shoulder being engageable by said pin to stop the segment upon its return to normal position from a lower case-shift position, 10 and said lower overlapped shoulder being engageable by said pin to stop the segment upon its return from an upper case-shift position, and said third shoulder being engageable by said pin to stop the segment at 15 an intermediate case-shift position, a first shift-key which when depressed first moves said device to cause one of said overlapped shoulders to clear said pin and then shift the segment in one direction to a final case-shift position, a second shift-key which when depressed first moves said device to cause said other overlapped shoulder to clear said pin and then shifts the segment to an intermediate case-shift position with 20 said pin against said third shoulder, a third shift-key which when depressed moves said device to cause one of said overlapped shoulders and also said third shoulder to clear said pin and then shifts the segment 25 to a final case-shift position beyond its said intermediate case-shift position, and stop-shoulders on said device to stop the segment at its final case-shift positions.

16. A front-strike type-bar typewriting machine comprising a main frame, a platen, a platen carriage mounted to travel on the main frame, an escapement mechanism for the carriage mounted on the main frame, a vibrating ribbon-guide mounted on the 30 main frame, a subsidiary frame detachably mounted in the main frame for removal therefrom, a type-action mounted on the subsidiary frame and comprising key-levers, an escapement-operating device having a 35 universal member operable by said key-levers, and mounted on the main frame, and a ribbon-guide-vibrating device mounted on the main frame and having a universal member operable by said key-levers, said 40 key-levers being withdrawn from said universal members by withdrawing the subsidiary frame from the main frame.

17. A front-strike typewriting machine having, in combination, a main frame, a 45 platen, a platen carriage mounted to travel on the main frame, an escapement mechanism for the carriage mounted on the main frame, a ribbon-vibrator mounted on the main frame, a subsidiary frame detachably 50 mounted in the main frame for removal therefrom, a type-bar segment carried by and shiftable upon the subsidiary frame, a type-action mounted on the subsidiary frame, and including type-bars pivoted on 55 the segment to shift therewith and also in-

cluding type-key-levers pivoted at their rear ends and having portions extending downwardly from their pivot points, an escapement-mechanism-operating device actuatable by said downwardly-extending portions of 70 the key-levers, and a ribbon-vibrator-operating device actuatable by said downwardly-extending portions of the key-levers.

18. A front-strike typewriting machine having, in combination, a main frame, a 75 platen, a platen carriage mounted to travel on the main frame, an escapement mechanism for the carriage mounted on the main frame, a ribbon-vibrator mounted on the main frame, a removable subsidiary frame 80 detachably mounted in the main frame, a type-bar segment carried by and shiftable upon the subsidiary frame, a type-action mounted on the subsidiary frame, and including type-bars pivoted on the segment to shift therewith, said type-action also including type-key-levers, a shift-key-lever for shifting the segment mounted on the subsidiary frame, a device for operating the 85 escapement mechanism from the type-action 90 mounted on the main frame and disconnectable from the type-action by the removal of the subsidiary frame from the main frame, and a device for vibrating the ribbon-vibrator from the type-action mounted 95 on the main frame and disconnectable from the type-action by the removal of the subsidiary frame from the main frame.

19. A front-strike typewriting machine having, in combination, a main frame, a non-shiftable platen, a platen carriage mounted to travel on the main frame, an escapement mechanism for the carriage mounted on the main frame, a ribbon-vibrator mounted on the main frame, a subsidiary frame detachably mounted in the main frame for removal through the bottom thereof, a shiftable type-bar segment mounted on the subsidiary frame, a set of type-bars pivoted on the segment to shift therewith and each having four types thereon, type-keys on the subsidiary frame to operate the type-bars, shift-keys for the segment on the subsidiary frame, and mechanism for operating the 100 escapement mechanism and the ribbon-vibrator from the type-keys and so arranged that removal of the subsidiary frame will break the operative relation between the 105 type-keys and the escapement mechanism 110 and the ribbon-vibrator, and such operative relation will again be established upon replacing the subsidiary frame through the bottom of the machine.

20. A front-strike typewriting machine having, in combination, a main frame, a non-shiftable platen, a platen carriage mounted to travel on the main frame, an escapement mechanism for the carriage mounted on the main frame, a ribbon-vibrator mounted on 115 the main frame, a removable subsidiary 120 frame, a type-bar segment carried by and shiftable upon the subsidiary frame, a type-action mounted on the subsidiary frame, and including type-bars pivoted on 125 the segment to shift therewith and also in-

- frame detachably mounted in the main frame, a type-bar segment shiftably mounted on the subsidiary frame and capable of occupying two final positions and two intermediate positions, a set of type-bars pivoted on the segment to shift therewith and each having four types thereon, type-keys on the subsidiary frame to operate the type-bars, shift-keys on the subsidiary frame for shifting the segment from normal position to any selected one of three case-shift positions, stops on the subsidiary frame for determining the final positions of the segment, movable stops on the subsidiary frame controlled by the shift-keys for determining the intermediate positions of the segment, and mechanism operated by the type-keys for operating the escapement mechanism and the ribbon-vibrator.
21. A front-strike typewriting machine having, in combination, a main frame, a non-shiftable platen, a platen carriage mounted to travel on the main frame, an escapement mechanism for the carriage mounted on the main frame, a ribbon-vibrator mounted on the main frame, a removable subsidiary frame detachably mounted in the main frame, a type-bar segment shiftably mounted on the subsidiary frame and capable of occupying two final positions and two intermediate positions, a set of type-bars pivoted on the segment to shift therewith and each having four types thereon, type-keys on the subsidiary frame to operate the type-bars, shift-keys on the subsidiary frame for shifting the segment from normal position to any selected one of three case-shift positions, stops on the subsidiary frame for determining the final positions of the segment, movable stops on the subsidiary frame controlled by the shift-keys for determining the intermediate positions of the segment, and mechanism on the main frame operated by the type-keys for operating the escapement mechanism and the ribbon-vibrator.
22. In a typewriting machine, in combination, a main frame, a platen, a platen-carriage mounted to travel on said main frame, escapement mechanism for said carriage, a ribbon-vibrator mounted for vertical movement on said main frame, a subsidiary frame detachably connected with said main frame for removal therefrom, a type-bar segment mounted for vertical movement on said subsidiary frame, a type-bar guide mounted on said segment to project upwardly immediately to the front of the ribbon-vibrator, key-levers pivoted in said subsidiary frame, and key-lever-actuable universal members for operating said escapement mechanism and said ribbon-vibrator, respectively, the operative connection between said key-levers and said universal members being broken by removal of said subsidiary frame and being re-established by inserting the subsidiary frame into the main frame.
23. In a typewriting machine, a platen, a platen-carriage, a main frame on which said carriage travels, a set of type-bars, a type-bar segment in which said type-bars are pivoted, key-levers for actuating said type-bars, and a subsidiary frame in which said segment and key-levers are mounted, said subsidiary frame comprising side members having uprights adjacent the rear ends thereof, a cross-member connecting said uprights, and a key-lever pivot-rod beneath said cross-member.
24. In a typewriting machine, a platen, a platen-carriage, a main frame on which said carriage travels, a set of type-bars, a type-bar segment in which said type-bars are pivoted, key-levers for actuating said type-bars, and a subsidiary frame in which said segment and key-levers are mounted, said subsidiary frame comprising side members having uprights adjacent the rear ends thereof, a cross-member connecting said uprights, a key-lever pivot-rod beneath said cross-member, and a cross-member joining said side members at the lower rear portion of the frame.
25. In a typewriting machine, a platen, a platen-carriage, a main frame on which said carriage travels, a set of type-bars, a type-bar segment in which said type-bars are pivoted, key-levers for actuating said type-bars, and a subsidiary frame in which said segment and key-levers are mounted, said subsidiary frame comprising side members having uprights adjacent the rear ends thereof, a cross-member connecting said uprights, a key-lever pivot-rod beneath said cross-member, a cross-member joining said side members at the lower rear portion of the frame, and a key-lever comb joining said side members at their forward ends and having its teeth extending downwardly.
26. In a typewriting machine, a platen, a platen-carriage, a main frame on which said carriage travels, a set of type-bars, a type-bar segment in which said type-bars are pivoted, key-levers for actuating said type-bars, and a subsidiary frame in which said segment and key-levers are mounted, said subsidiary frame comprising side members having uprights adjacent the rear ends thereof, a cross-member connecting said uprights, a key-lever pivot-rod beneath said cross-member, a cross-member joining said side members at the lower rear portion of the frame, a key-lever comb joining said side members at their forward ends and having its teeth extending downwardly, and a cross-member joining the side members at their lower edges and near their front ends.
